ELECTRICAL APPARATUS

Leo Rosen, United States Army,
Arlington County, Va.

Application August 1, 1945, Serial No. 608,342

9 Claims. (Cl. 250—152)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention is in electron tubes and particularly is a novel cathode ray tube with a plurality of plate structures.

The principal object of this invention is to provide an electron tube which will effectively measure the amplitude of a fluctuating signal at selected intervals, and provide an output for a particular plate circuit, the choice of the plate depending upon the amplitude of the input at the instant of measurement.

Another object is to provide an electron tube in which the choice of an output circuit will depend in the first instance only on the value of the input signal, a change in input voltage subsequent to such time having no effect on the output of the tube.

An additional object of this invention is to provide a tube wherein two or more independent voltages may be combined vectorially and their sum treated as mentioned in the preceding objects.

Other objects will be apparent from a reading of the following specification and claims.

In the drawings:

Figure 1 is a diagrammatic representation of the tube of my invention;

Figure 2 is a similar diagram of a modified form of the tube in which two varying voltages may be combined;

Figure 3 represents in diagram an input signal for the tube of Figure 1 and the corresponding output signal thereof; and

Figure 4 shows a representative two-signal input for the tube of Figure 2 and the output corresponding thereto.

In the showing of Figure 1, 10 is a cathode which serves as the source of electrons for the tube, the electrons being susceptible of being formed into a beam 11 by means of electrode 12, of being deflected in customary fashion by plates 13, 14, and 15, and of being turned on or off by the application of proper control voltages to grid 16. The cathode is heated in conventional fashion by a filament 10'.

Each of the target structures comprises a target electrode, as 20, 21, and 22, and a pair of supplementary electrodes one on each extremity of the target, all plate members being aligned across the target end of the tube so that all can be swept by the electron beam moving in one plane.

Two amplifiers 24 and 25 are provided. The

electrode elements 26, 27, and 28 and the other electrode elements in similar relationships to their principal electrodes are adapted to feed into amplifier 25, whereas electrodes 30, 31, and 32 and others similarly juxtaposed to their central electrodes are adapted to feed into amplifier 24. The outputs of the amplifiers in turn are applied to deflecting plates 14 and 15. Normally, the outputs of the two amplifiers are balanced and have no effect on an electron beam in the tube.

Now assume a fluctuating voltage to be applied to deflecting element 13, and the beam to be turned on through the application of the proper voltage to grid 16. As the beam goes on, it will be deflected in some fashion and will strike a target electrode, for example, 21, and a signal will appear on output lead 21'. Any subsequent change in the voltage, acting through the deflecting structure 13 will tend to cause the beam to strike one of the adjacent electrodes 27 or 31. Should it strike electrode 27, a signal will be furnished to amplifier 25, resulting in the energization of deflecting structure 14 such as to produce a deflection in the electron beam approximately equal and opposite to the deflection caused by the fluctuation in the value of the input of the tube. On the other hand, should the beam move in the opposite direction in response to a variation in input voltage, and strike electrode 31, a signal will be provided through amplifier 24 to deflecting structure 15, the effect being again to move the beam back to target electrode 21. The beam will thus remain on a target electrode until it is turned off through grid 16.

If the beam is cut off and turned on once again, it will strike a target electrode of the group 20, 21, 22, etc., the selection being based upon the value of the voltage on deflecting structure 13 when the tube is energized. The sequence of operations is shown graphically in Figure 3. The pulses indicated at 35' are applied to the grid 16 of the tube and determine the commencement and durations of the output signals. Normally, the pulses will be equal in duration and regularly spaced; but the use to which the device is to be put will determine the characteristics of the timing pulses.

Obviously, other means for deflecting the cathode ray beam may be employed; the principles of operation remain the same. Further, the input signal or signals may be applied to deflecting plates 14 and 15, and structure 13 eliminated.

It will be apparent also that the beam 11 may be shaped as desired just as the beam in a con-

ventional cathode ray tube, the shaping normally depending upon the nature of the receiving or target electrode; and that, in place of the timing pulses on grid 16, any means for neutralizing or balancing the outputs of amplifiers 24 and 25 can be utilized to permit movement of the electron beam from one target to another, as, for example, by grounding the outputs.

Two voltages may be effectively combined by the tube of Figure 2. The modified tube has two inputs 35 and 36, with deflecting structures 40 and 41, respectively, in place of the single input and deflecting means 13 of Figure 1. Normally, only three target electrodes will be used in this embodiment of the invention, and three are shown, 42, 43, and 44. A single output line 45 serves targets 42 and 43, and another output line is provided for plate member 44.

This tube is intended particularly to combine two signals, each having but two possible values. Thus, it is well suited to the addition of two Teletype-like signals. Such addition is commonly performed according to the so-called Vernam rule which provides that, when two marking signals or two spacing signals are added, a spacing signal is transmitted, whereas, when two unlike signals are added, a marking signal is transmitted. The action is illustrated in Figure 4 wherein A represents one on-off signal and B, another such signal. The "arithmetical" sum of two marking signals is shown at C, of a marking signal and a spacing signal, at D, and of two spacing signals, at E. The output of the tube of Figure 2 may be seen at F and G, it being understood that, when a marking signal and a spacing signal are applied simultaneously to the inputs 35 and 36, the electron beam is not deflected (the signals effectively balancing each other through deflecting structures 40 and 41), where two marking signals are applied simultaneously, the beam is deflected to target 42 (for example), and, when two spacing signals are applied, to target 43. The conditions of the input signals at the beginning of a time interval control the output for the duration of the interval.

It should be understood that the tube now being described is not limited in its action to the treatment of Teletype or other two-value signals. Two irregularly fluctuating voltages may be applied to the two deflecting plate structures 40 and 41. Their effect upon any electron beam which may be directed through the tube will amount to the vectorial sum of the two applied signals. The pulses 50 of Figure 4 in effect sample the two signals under study at intervals which may be regular or timed in whatever manner desired.

Under certain conditions, it may be desirable not to rely altogether upon the current of the cathode ray beam. In such a case, the electrodes of the groups 20, 21, and 22, Figure 1, and 42, 43, and 45, Figure 2, are rendered secondarily emissive. Electrodes 50 (Figure 1) and 51 (Figure 2) are utilized as collectors in a manner well known in the art. The sense of the currents in the several output leads will be then opposite in all cases to that just described, but the operation of the tube will be substantially as previously indicated.

Through the use of additional deflecting plates and receiving electrodes, the tubes shown herein may be suited for two-dimensional operation. The output electrode at a particular instant is fixed by coordinates defined by horizontal and vertical deflecting voltages.

The tube envelopes shown in the drawings are approximately conventional, but the envelopes

may take other forms. The output of the tube can be increased, and certain other advantages obtained, by making the envelope circular—like a flattened barrel—with the cathode in the center. The targets and auxiliary electrodes assume ring shapes, as do the focusing means, deflecting plates, and grid, and the beam becomes a disk.

The foregoing description is in specific terms, and many modifications will readily occur to those skilled in the art. The invention is not, therefore, to be construed to be limited by the description and drawings except as required by the appended claims.

I claim:

1. In a device of the nature described, means for generating an electron beam, a plurality of means responsive to electrical signals for deflecting said beam, a plurality of target electrodes, a plurality of pairs of additional electrodes each of said pairs having one of said first-mentioned target electrodes spaced therebetween and partially overlapped in relation to said beam by the electrodes of its pair of additional electrodes each electrode of a said pair being adapted under impingement by said beam to furnish an electrical signal to deflect said beam toward its interspaced target electrode.

2. In a device of the nature described, means for generating an electron beam, switching means for turning on and off said beam at predetermined intervals, a plurality of means for deflecting said beam within a predetermined plane, a target electrode for said beam and an auxiliary electrode adjacent each side of said target electrode and within said plane adapted under impingement by said beam to furnish an electrical signal to a deflecting means to deflect said beam toward said target electrode.

3. In a device of the nature described, means for generating an electron beam, a plurality of means for deflecting said beam, a first output line, a target electrode adapted under impingement by said beam to provide a signal to said line, other target electrodes adjacent said first mentioned target electrode said other target electrodes being adapted under impingement by said beam to supply signals to a second common output line, and additional electrodes adjacent said target electrodes adapted under impingement by said beam to supply signals to deflect the same toward the adjacent target electrode.

4. The invention of claim 3, wherein certain of said other target electrodes are aligned with and on both sides of said first mentioned target electrode.

5. The method of sampling a fluctuable signal which includes creating a field responsive solely to said signal, forming an electron beam the direction of said beam depending upon said field at the instant of sampling and thereby indicating a value of said fluctuable signal, and preventing substantial change in said direction by creating additional fields about said beam to oppose progression and regression thereof.

6. The method of sampling a fluctuable signal which includes creating a field responsive solely to said signal, forming an on-off electron beam the direction of said beam at the beginning of an interval depending upon said field at the instant of sampling and thereby indicating a value of said fluctuable signal, and preventing substantial change in said direction by creating additional fields about said beam to oppose pro-

gression and regression thereof during an on interval.

7. The method of sampling a two-level signal which includes creating a field responsive solely to said signal, directing an intermittent electron beam through said field, said field acting initially only in the on intervals of said beam to deflect the same substantially predetermined directions and distances thereby to indicate successive values of said signal at the beginnings of said on intervals, creating immediately subsequent to said initial action additional fields about said beam responsive to progressive and regressive movements thereof to oppose such movements and generating output signals in response to said beam.

8. The method of combining two fluctuable signals which includes creating a field responsive to one fluctuable signal, creating another field responsive to the other fluctuable signal, directing an on-off electron beam through said fields, intermittently creating fields substantially opposite in sense to changes in said first mentioned fields during on intervals of said beam, and generating output signals in response to said beam.

9. In a device of the nature described, means

5
